[57] CLAIM

The ornamental design for shelving support unit, as shown and described.

DESCRIPTION

FIG. 1 is a front elevational view of the design;

FIG. 2 is an elevational view of one side thereof, the opposite side being identical; and

FIG. 3 is an enlarged perspective view of one of the support brackets detached from the supporting board;

FIG. 4 is a perspective view of a second support bracket detached from the supporting board; and,

FIG. 5 is a perspective view of a third support bracket detached from the supporting board.

The shelving support brackets are shown detached in FIGS. 3-5 for clarity illustration.

The rear view of the claimed design is planar and unornamented. Likewise, the rear view of each individual support bracket is planar and unornamented.
